(57) **CLAIM**

The ornamental design for a scooter, as shown and described.

DESCRIPTION

1.1 is a front view of a scooter showing our new design;

1.2 is a back view thereof;

1.3 is a left view thereof;

1.4 is a right view thereof;

1.5 is a top view thereof;

1.6 is a bottom view thereof;

1.7 is a first perspective view thereof; and

1.8 is a second perspective view thereof.

Each of FIGS. 1.1-1.8 includes colored portions showing unclaimed subject matter of the scooter that form no part of the claimed design.

1 Claim, 6 Drawing Sheets
